UNITED STATES PATENT OFFICE.

OTTO SCHAEERER, OF ZURICH, SWITZERLAND.

ROTATING CUTTER.

SPECIFICATION forming part of Letters Patent No. 690,323, dated December 31, 1901.

Application filed June 5, 1900. Serial No. 19,099. (No model.)

To all whom it may concern:

Be it known that I, OTTO SCHAEERER, a citizen of the Republic of Switzerland, and a resident of Grünasse 6, Zurich, Switzerland, have invented certain new and useful Improvements in Rotating Cutters, of which the following is a full, clear, and exact specification.

This invention consists in means whereby the cutter may be thrown out of gear.

In the accompanying drawings, Figure 1 is a side view of the machine, partly in section. Fig. 2 is an end view, and Fig. 3 a cross-sectional view, of the machine. Fig. 4 is a longitudinal section of the cylinder and adjacent parts. Fig. 5 is a plan view of a detail. Fig. 6 is a diagram illustrating the working of the invention. Fig. 7 is a view of a detail.

Referring to Fig. 1, the head-stock *a* is supported on a bed *w* between the tailpiece-spindle *s* and the main carriage. A cylinder *b* is supported in the head-stock *a*, and in the cylinder *b* a hollow cylinder *c* is placed eccentric thereto. This latter cylinder is to hold the work-piece. A gear *d* is fixed on the cylinder *b*, which engages a pinion *p*, driven from a gear *e*, carried by a sleeve *g*, supported on a pin *e'*, said sleeve being oscillated by an arm *f*, a slot in which receives a pin *x*, connected with the tail-stock spindle, so that the rotation of the tail-stock spindle will oscillate this slotted arm *f* and through the gearing described impart a rotary oscillating movement to the cylinder *b*. The eccentrically-arranged cylinder *c* has on its rear end a ratchet-wheel *h*, with which engages a pawl *i*, pivoted to the gear *d*. A spring-pressed detent *k*, carried by a bracket *k'*, adjustably held by a set-screw *k''* to an arc-shaped part *u* of the frame, engages the ratchet-wheel *h* to prevent backward movement thereof. A sleeve *l* is fastened to the cylinder *b*, and it has inclined slots *m m'*, adapted to be engaged by a pin *n*, supported on the head-stock. When this pin *n* engages one of the inclined slots, the rotary movement of the cylinder *b* will cause the pin and slot to produce a longitudinal movement of the cylinder.

The ungearing of the cutter is effected in the following manner: The tail-stock spindle

through the described connections produces a continuous oscillatory motion of the cylinder *b*. This causes the tool-holding cylinder to have a swinging movement as a whole about the center of rotation of the carrying-cylinder *b*. In Fig. 6 the course of movement of this cylinder *c* is represented by 1 2.

During the rotation of the cylinder *b* the cylinder *c* is moved by means of the pawl *i*, Fig. 2. As soon as this movement has been effected in one direction the cylinder *b* swings back in the opposite direction; but in this movement the pawl *k* engages the ratchet-wheel *h* and holds the same against rotation, so that a relative displacement takes place between the hollow cylinder *c* and the carrying-cylinder *b*. If the cutter is to be ungeared at the surface only, it is necessary to place the screw *n* up high and to fasten the sleeve *l* onto the fore part of the cylinder *b*. In this manner the sleeve serves to confine the spindle while in motion.

I claim—

1. In combination, a head-stock, a carrying-cylinder revolving therein, a cylinder eccentrically arranged within the carrying-cylinder, said eccentric cylinder being arranged to support the cutter, means for giving the carrying-cylinder an oscillatory motion, means whereby the two cylinders are connected and the eccentric cylinder partakes of the motion of the carrying-cylinder and means whereby the eccentric cylinder will be held against movement on the return movement of the carrying-cylinder whereby the cutter is given an interrupted, intermittent eccentric oscillatory movement.

2. In combination, the head-stock, a cylinder, means for oscillating the cylinder therein, a sleeve adjustably attached to the cylinder and having inclined grooves, a pin on the head-stock adapted to engage one or the other of said grooves, to produce a longitudinal movement at each oscillation of the cylinder.

In witness whereof I have hereunto set my hand in presence of two witnesses.

OTTO SCHAEERER.
